UNITED STATES PATENT OFFICE

149,970

DESIGN FOR AN ANDIRON

John W. Rehfuss, Albany, N. Y.

Application July 3, 1946, Serial No. 131,290

Term of patent 14 years

(Cl. D81—6)

To all whom it may concern:

Be it known that I, John W. Rehfuss, a citizen of the United States, residing at Albany, in the county of Albany and State of New York, have invented a new, original, and ornamental Design for an Andiron, of which the following is a specification, reference being had to the accompanying drawing, forming a part thereof in which

Fig. 1 is a front elevational view of an andiron showing my new design;

Fig. 2 is a side elevational view thereof;

Fig. 3 is a top plan view thereof; and

Figs. 4 to 29, inclusive, are small scale front elevational views of the design with the other letters of the alphabet, including Mc used thereon.

The dominant features of my design for the andiron disclosed reside in the configuration of the base portion illustrated surmounted by an

upright in the form of one of the letters of the alphabet of the specific type shown.

I claim:

The ornamental design for an andiron, as shown and described.

JOHN W. REHFUSS.
